ATTORNEYS

UNITED STATES PATENT OFFICE.

JACOB H. BARNETT, OF NEW YORK, N. Y.

TROUSERS.

1,411,149.

Specification of Letters Patent. Patented Mar. 28, 1922.

Application filed December 28, 1920. Serial No. 433,648.

To all whom it may concern:

Be it known that I, JACOB H. BARNETT, a citizen of the United States, and a resident of the city of New York, borough of 5 Manhattan, in the county and State of New York, have invented new and Improved Trousers, of which the following is a full, clear, and exact description.

This invention relates to trousers and also 10 for wearing apparel and has for an object to provide an improved construction of seam wherein an extra strip is provided which may be actuated for breaking the stitching of the seams without injuring the garment.

Another object in view is to provide in 15 a garment of any kind a ripping strip held in place by the same stitches that is used to hold the parts of the garment together.

A further object more specifically is to 20 provide a ripping strip and socket for trousers wherein a ripping strip may be placed in any or all of the seams of the trousers and the socket structure arranged at the rear of the waist band for permitting 25 easy opening of the seams at that point.

In the accompanying drawings—

Figure 1 is a perspective view of the upper part of the pair of trousers having the ripping strips arranged thereon.

Figure 2 is a fragmentary sectional view 30 through Figure 1 on line 2—2, the same being on an enlarged scale.

Figure 3 is a fragmentary view similar 35 to the central rear part of that shown in Figure 1 except certain of the parts have been ripped and thrown back.

Figure 4 is a view similar to Figure 3 but 40 with the parts further separated and disclosing to view the ripping strip associated with the back seam of the seat of the trousers.

Figure 5 is a fragmentary sectional view 45 on an enlarged scale through Figure 1 on line 5—5.

Referring to the accompanying drawings 50 by numeral, 1 indicates a pair of trousers of any desired construction. The invention has been shown in connection with a pair of trousers but it will be understood that the tearing strip particularly illustrated in Figures 4 and 5 may be used with other garments without departing from the spirit of the invention.

As shown in Figures 1 to 4 inclusive, the trousers 1 is provided with a central rear 55 seam 2 in the seat, said seam being provided with an appreciable allowance so that

the seam may be let out or taken in as desired to secure the desired fit. In addition to the allowance provided for seam 2 the band 3 and the upper edge of the trousers 60 must be made so that the waist measurement may be increased or decreased as may be desired. In order to do this the band seam 4 is opened and usually seam 2 opened for a short distance after which the band 3 and associated parts are arranged to secure 65 the proper measurement and the new stitching provided in seams 2 and 4.

Heretofore, when it was desired to let out or take in seam 2 and let out or take in 70 seam 4, it was necessary for a workman to open up these seams with a knife or other suitable cutting instrument and in doing so much time was lost. In addition, the workman sometimes would cut the goods forming 75 part of the garment and, consequently, would injure the garment to that extent. According to the present invention, the idea of opening up the seam for letting out the trousers or taking in the seam is the same as heretofore done but instead of cutting with 80 a knife or other instrument the threads of the seam, ripping strips or members have been provided whereby the seams may be opened without any instruments other than the hands. During the formation of the 85 seam 5 which is interrupted at 6 and 7, a tearing strip 9 is provided and arranged with one end extending beneath part of the band 3 and the opposite end overlapping the seam 4 as shown in Figure 1. When 90 the machine makes the seam 5, the strip 9 is stitched in place simultaneously with the other parts of the garment.

When it is desired to open up seam 4, 95 which is really a continuation of seam 2, strip 9 is pulled in a downward direction when the parts are as shown in Figure 1. This will break the threads of seam 5 adjacent the seam 4. The fingers are then inserted into the openings 6 and 7 and the ears or flaps 10 100 and 11 are grasped and pulled whereupon the remaining part of seam 5 between the openings 6 and 7 will be ripped or broken so as to expose the ripping strip 12 arranged along the seam 2 which strip extends upwardly across seam 4 which, as above stated, 105 is merely a continuation of seam 2. This ripping strip consists of one, two or more strips of some strong cloth and is stitched in place as shown in Figure 5 with the same 110 stitching that holds the garment together along seam 2. Where the goods of the gar-

ment is strong, the end of the strip 12 is grasped and pulled. This will cause the threads of the seam 2 to break. If the material of the garment is comparatively weak 5 the inner layer of the strip 12 only is grasped by one hand and the other strip held by the opposite hand. The inner strip is then pulled and the strain will, therefore, be principally between the two strips or layers 10 of strip 12. This will effectively break the threads of the seam without the use of an instrument.

Where it is desired to let out the seam 2 after the parts have been opened up as 15 shown in Figure 4, a new seam is provided between the seam 2 and the outer edges of the flaps 13 and 14. After this new seam has been provided strip 12 is removed as above described and that part of the work 20 is completed. In case the seam 2 was to be taken in a proper seam will be provided on the opposite side of the strip 12 to that just mentioned before the strip is removed and then said strip 12 is removed so that the flaps 25 13 and 14 may be properly pressed down. After the new seam 2 has been provided the

waist band and associated parts are again assembled and stitched down as shown in Figure 1.

What I claim is:—

1. In a pair of trousers of the character described a waist band arranged at the upper part of the interior of the trousers, a tearing strip straddling said waist band and a retaining seam of stitching extending around the band adjacent the lower edge, said stitching extending across said tearing strip and provided with a gap at a short distance on each side of the tearing strip. 30

2. In a pair of trousers of the character described a band having adjacent ends bent back upon themselves and formed with extending ears, means for connecting the ends of said band together and a retaining line of stitching arranged adjacent the lower edge 40 of said band formed with an unstitched section adjacent the ends of said ears whereby the workmen may grasp either of said ears for using the same as a tearing strip for breaking the line of stitching adjacent said ears. 45

JACOB H. BARNETT.
